UNITED STATES PATENT OFFICE.

WALTER PIERNAY, OF STETTIN, GERMANY, ASSIGNOR TO STETTINER CHAMOTTE-FABRIC AKTIENGESELLSCHAFT VORMALS DIDIER, OF STETTIN, GERMANY.

APPARATUS FOR INCINERATING REFUSE.

Application filed June 9, 1922. Serial No. 567,016.

My invention relates to a method of and means for incinerating refuse or other fuel, by a process in which heated air, or air mixed with steam is caused to pass through 5 highly heated slag or ashes and thence into the fuel to be consumed, so as to form combustible gases, which may be usefully burned or otherwise employed.

My invention aims to supply a comprehensive system of refuse incineration and power generation, so constructed and organized as to secure the highest possible efficiency and to require the minimum attention. I have provided means for charging the 10 furnace and removing waste products designed with regard to the character of the fuel and waste products handled, to enable the charging and discharging to be effected with the minimum inconvenience from dust and the least attention. I have so designed and constructed the furnace of my invention that the thermal effect of the gases generated is used most efficiently and a minimum amount of waste products is permitted to 15 escape by way of the stack. Means are also provided whereby combustion of the charge may take place under forced draft without the escape of the products of combustion or waste products.

Other objects and advantages of my invention will be apparent from the following specification and will be more particularly pointed out in the claims, it being understood, however, that the particular embodiments of my invention shown in this specification and in the drawings are shown by way of example only and that I do not intend to confine myself thereto, as many changes may be made without departing from the spirit 20 of my invention.

In the drawings, I have shown:

In Fig. 1, a sectional view of my improved furnace;

In Fig. 2, a detail sectional view of the 5 charging carriage;

In Fig. 3, a plan view showing the charging carriage and furnace cover;

In Fig. 4, a detail view of the slag cutting knife; and

In Fig. 5, a detail view of the furnace sole and its associated mechanism.

Referring to the drawings, it will be seen that my improved furnace comprises a shaft having a lining which comprises an iron 5 mantle 1, which is preferably water-cooled,

in order to prevent the slag formed in the operation of the furnace from adhering to its walls. The mantle may be conveniently formed of sheet iron or steel welded electrically, or in any other suitable manner, 60 and is preferably horizontally ribbed, as at 2, to permit unequal expansion of its outer and inner walls. The mantle is supported by hanging it from brackets, stay bolts, or the like located near its upper end and preferably above the ribs 2. Suitable water or other cooling fluid supply pipes 3 and 4 are provided and suitable provision for cooling the water is made. Such means being well-known are not here shown or described. 65 The mantle is bricked into the furnace structure, care being taken to permit its free expansion and contraction and the furnace head 5 is therefore arranged so that it will not bear upon the top of the mantle. 70

Located adjacent the lower end of the mantle is a plurality of air inlets 6, which may be of the form shown and described in my United States Patent Number 1,346,055, said air inlets being supplied by an air duct 7, which is in turn supplied by suitable air pipes 8. At the bottom of the furnace the slag cutter 9 is located. I have found that much better results are secured by extending the mantle 1 as far down as the slag 85 cutter instead of stopping it at a higher level as was thought necessary heretofore, the freedom of movement of the slag and consequently of the entire charge of the furnace being greatly enhanced. The slag cutter 9 is adapted to be intermittently operated when it is desired to draw off slag and ashes, as will be described hereafter, the slag cutter being operated by a compressed air or hydraulic cylinder 10, or other suitable 90 source of power. At the bottom of the furnace, below the slag cutter 9, is located an ash-pit 11 closed by the removable sole 12.

The sole 12 is preferably made of fire-brick, or similar refractory material and is 100 mounted upon carriage 13 adapted to ride on rails 14. Rails 14 are pivotally mounted, as at 15, to enable the sole to be moved upwardly to close the ash-pit.

Carriage 13 is moved along rails 14 by 105 means of the pneumatic or hydraulic cylinder 16, or other suitable source of power and rails 14 are moved upwardly and downwardly by a suitable source of power, such as the hydraulic or pneumatic cylinder 17. 110

The waste products are removed in cars 18. Surrounding the sole carriage 13 and its associated parts and extending to within close proximity of the car 18 is a hood 20, which is connected to an exhaust pipe 21, within which a partial vacuum is maintained by any suitable means, as for instance, by means of an injector operated by the compressed air used in the air inlets 6. The hood 20 and exhaust pipe 21 serve to prevent the scattering of the fine ashes falling from the furnace when the dumping mechanism is operated.

At the upper end of the furnace, I provide means for charging the furnace and for maintaining the furnace closed at all times. These means include a carriage 22, carrying a cover of firebrick or other suitable material adapted to run on the rails 23 mounted above the furnace. Also operating on rails 23 is the charging carriage 24 which may be adapted to carry cans of refuse and to dump the cans into the furnace. The particular construction of the carriage and dumping mechanism is not described here as they form the subject-matter of a co-pending application, filed June 9th, 1922, Serial No. 567,017.

When furnaces of the construction described herein are operated in batteries, it is sometimes convenient to so locate the furnaces and their cover and charging carriages that one charging carriage may serve two furnaces. Charging carriage 24 is preferably made of sheet steel and is provided with doors 25, preferably self-closing, to prevent the escape of gases or the products of combustion during the charging operation. Both charging carriage 24 and cover carriage 22 are provided with recesses within which flexible gaskets 26 are fixed, to assist in sealing the top of the furnace and are so arranged with respect to the brickwork of the top of the furnace as to seal the top of the furnace as nearly as possible.

Rails 23 are preferably supported over a water bath 27, which acts to catch escaping dust and to assist in cooling the upper part of the furnace and the mechanism mounted thereon.

The foregoing describes the combustion and gas generating portion of the furnace; I shall now describe the power generating portions combined therewith.

The gases, after generation in the mantle 1, pass out through a path comprising a plurality of baffle walls, 28 to 32, inclusive. Said walls are so arranged as to provide vertical flues having ash-pits 33, 34 and 35 at their lower extremities. It will be understood that in the operation of my improved furnace, the gases generated carry over a large amount of fine ashes or dust and that some of the gases are relatively slow burning. It is therefore desirable to provide a relatively

long path for the gases, to permit their combustion and to provide means for readily removing the suspended solid matter. The ash-pits in which the flue dust collects are therefore connected to the cars 36, or other suitable means are provided for their evacuation. In practice, it is desirable to maintain a quantity of ashes in the ash-pits, as they are very highly heated and thus contribute to the efficiency of the apparatus as a whole.

Located remote from the gas generating end of the furnace is the boiler 37 which may be of any suitable type and may be provided with a superheater 38 if desired.

In the boiler chamber, I also locate the primary air heater 39 in which the air afterwards used in the combustion of the fuel is given its first heating. The air, after having been heated in heater 39 is led to the secondary heater 40 located in baffle wall 28 and thence to air service pipes 8. I have found it desirable, on account of the very high temperature of baffle wall 28, to give the air a preliminary heating, to avoid too great an expansion in heater 40, but if suitable provision for such expansion can be made, the preliminary heating may be dispensed with.

It will be noted that in my improved furnace there is no grate and that the furnace is charged and discharged by measured quantities. I am thus enabled to keep the level of the ashes or slag substantially constant and to properly regulate this level with relation to the air supply, to secure maximum efficiency.

In my improved furnace, I produce a burning of the refuse in one zone, air being supplied thereto through a zone of slag or ashes, and a destructive distillation of the fuel and a drying of wet organic matter in upper zones. The process is therefore continuous.

In the operation of the furnace of my invention, a charge is fed to the furnace by first moving the cover carriage from the top of the furnace, preferably by pushing it with the charging carriage so as to prevent any escape of the products of combustion during the change from one carriage to another, and by dumping the charge in any suitable manner, such as that described in my said co-pending application. During the dumping of the charge, the doors 25 are opened, but at other times, while the charging carriage is in position, they are maintained closed. Preheated air is admitted through the nozzles 6, as previously described, at a suitable pressure and cooling water is circulated through the mantle. When it is desired to remove a portion of the accumulated waste products, the air is shut off and is passed into the injector to produce a vacuum in pipe 21 and hood 20

and the slag cutting knife 9 is advanced into the position of Fig. 1. The sole 12, which has been in the position of Fig. 1 during the operation of the furnace, is then dropped by moving rails 14 about pivot 15 and the sole is withdrawn from under the ash-pit, thus dropping the ashes into car 18. The furnace being dumped, the sole 12 is again returned to position and the cutting knife 10 then withdrawn, thus permitting an accumulation of slag and ashes to drop in the sole and lowering the level of the charge in the furnace by the depth of the ash-pit 11.

It will be understood that suitable control mechanism 41 and 42 is provided for the air and for the operation of the slag knife and sole mechanism, but as such mechanism may take widely varying forms, it will not be described in detail.

20 In the actual operation of my furnace, operating on garbage, city refuse and coal ashes, the following approximate temperatures have been noted:

	Deg. F.
25 Ash-pit	350
Slag zone	900
Combustion zone	2,500
Top of mantle	2,400
First baffle wall	2,300
30 Boiler chamber	1,550
Stack	542

It will be noted from the foregoing temperatures that the temperature of the ash-pit is such as to permit of convenient dumping of the furnace and that no large amount of heat is lost in the waste material. The temperature of the slag zone is sufficiently elevated to impart to the air distributed therethrough a considerable amount of heat or to prevent preheated air from being unduly cooled. The temperature of the combustion zone is ample to cause destructive distillation of the material. As the gas leaves the furnace, it is burning at a high temperature, 2400 degrees F., which temperature is substantially maintained when it strikes the first baffle wall in which the second stage of the air preheater is located. 40 It will also be noted that complete combustion of the gases takes place, delivering the maximum possible heat to the boiler and the minimum to the stack.

50 What I claim is:

1. In a furnace adapted to operate upon refuse or similar fuel, a combustion and gas generating chamber, a gas combustion chamber comprising a plurality of baffle walls, and a steam generating chamber located remote from the combustion and gas generating chamber, primary air preheating means in said steam generating chamber and secondary air preheating means in said gas combustion chamber.
- 60 2. In a furnace adapted to operate upon

refuse or similar fuel, a combustion and gas generating chamber, having no grate and closed walls and operating under forced draft, a gas combustion chamber comprising a plurality of baffle walls and a steam 70 generating chamber located remote from the combustion and gas generating chamber, primary air preheating means in said steam generating chamber and secondary air preheating means in said gas combustion chamber. 75

3. In a furnace adapted to operate upon refuse or similar fuel, a combustion and gas generating chamber, within which a portion of the fuel is adapted to be burned and 80 a portion destructively distilled into combustible gases, a gas combustion chamber comprising a plurality of baffle walls and a steam generating chamber located remote from the combustion and gas generating 85 chamber, primary air preheating means in said steam generating chamber and secondary air preheating means in said gas combustion chamber.

4. In a furnace adapted to operate upon refuse or similar fuel, a combustion and gas generating chamber, having a closed top and walls and having no grate and adapted to operate under forced draft, within which a portion of the fuel is adapted to be burned 90 and a portion destructively distilled into combustible gases, a gas combustion chamber of a length sufficient to enable the said gases to be burned and a steam boiler located at the end of said gas combustion chamber, primary air preheating means in said steam generating chamber and secondary air preheating means in said gas combustion chamber. 100

5. In a furnace adapted to operate upon refuse or similar fuel, a combustion and gas generating chamber, a gas combustion chamber comprising a plurality of walls providing an elongated path for said gas, a steam generating chamber located at the end of the gas combustion chamber, a primary air heater located in the steam generating chamber and a secondary air heater located in one of said baffle walls. 105

6. In a furnace adapted to operate upon refuse or similar fuel, a combustion and gas generating chamber, a gas combustion chamber, a primary air heater located remote from the combustion and gas generating chamber and a secondary air heater located 110 in the gas combustion chamber and in proximity to the combustion and gas generating chamber. 120

7. In a furnace adapted to produce gas from refuse or the like, a gas generating chamber, a gas combustion chamber comprising a plurality of staggered baffle walls arranged to provide an elongated path for the combustible gases, an air preheater in one of said baffle walls and leading to the 125 130

lower portion of the gas generating chamber, the floor of the combustion chamber between alternate walls being arranged to form ash-pits to collect suspended solids in the gas and means for evacuating the ash-pits.

8. In a furnace adapted to produce gas from refuse or the like, a gas generating chamber, a gas combustion chamber comprising a plurality of baffle walls having openings alternately at the top and bottom thereof, the floor of the furnace between baffle walls having openings at the top being

inclined downwardly to form ash-pits to receive suspended solid matter from the gases and means for evacuating the ash-pits, means in said baffle walls for preheating air and means for admitting said preheated air to the lower portion of the gas generating chamber whereby said air is distributed throughout the fuel mass in the gas generating chamber.

In testimony whereof, I have signed my name to this specification this sixth day of May, 1922.

WALTER PIERNAY.
